UNITED STATES PATENT OFFICE.

WILBERT L. DREW, OF COVINA, CALIFORNIA.

FACE PACK.

Application filed December 5, 1927. Serial No. 237,873.

My invention relates to face packs adapted for steaming the face to soften the beard incident to shaving and for otherwise treating the face with hot or cold applications.

5 It is a purpose of my invention to provide a face pack simplified in construction to permit manufacturing at a relative low cost, and facilitating the quick and thorough application of a hot or cold pack to the face, 10 the device operating to maintain a mask in contiguous relation to the face so as to leave the hands free.

It is also a purpose of my invention to provide in a face pack a mask constructed 15 to snugly conform to and completely cover the chin and sides of the face so as to render the pack highly effective particularly in steaming and softening the beard.

I will describe only one form of face pack 20 embodying my invention and will then point out the novel features in claims.

Fig. 1 is a view showing in perspective one form of face pack embodying my invention in applied position;

25 Fig. 2 is a view showing in side elevation and in extended position the mask embodied in the pack shown in Fig. 1;

Fig. 3 is a detail view of one of the sections of the mask shown in Fig. 2.

30 My invention in its present embodiment comprises a mask designated generally at M and constructed of any suitable material such as Turkish toweling, the mask being made up in the present instance of four sections of toweling, each section being designated at 15 and of the contour shown in Fig. 3. The mask sections are arranged in pairs, each pair being stitched or otherwise secured to each other to form one thickness 35 of material, and the two pairs being stitched to each other at their outer edges so as to form a mask of two thicknesses. As illustrated in Fig. 3, the inner edge, indicated at 15^a, of each section 15 is curved, as illustrated, so that when stitched to the corresponding edge of the companion section the two sections will coact to provide a chin-receiving portion 16 of such contour as to receive and snugly fit the chin.

50 The sections 15 are constructed to provide extensions 17 at the sides of the mask which, in the applied position to the face, extend upwardly of and cover those portions of the sides of the face which are usually shaven. In addition to the outer edges of 55 the mask sections being stitched to each

other, they are bound at such edges by strips of tape 18 folded so as to cover the mask edges and thereby serving to reinforce the mask as a whole and to prevent unraveling 60 of the material of which it is formed.

The mask is held upon the face in the manner illustrated in Fig. 1, and by the provision of a supporting device which, in the present instance, comprises a head-em- 65 bracing frame F and a chin-embracing frame C, both of which are formed of any suitable, semirigid material such as resilient metal. The frame F as now made consists of a single length of strap metal bent into substantially 70 ovate form and having its ends in overlapped relation when in applied position and adjustably secured to each other so as to cause the form to snugly embrace the head in the manner illustrated in Fig. 1. 75 The frame ends are adjustably connected by the formation in one end of key-holes 19, and headed members 20 secured to the other end, the holes and members being arranged at regular and corresponding intervals along 80 the frame to permit of a longitudinal adjustment of the frame ends and the securing of such ends in any adjusted position. In this manner the frame can be accommodated to heads of different sizes and when in applied position to snugly embrace the head 85 to prevent the accidental displacement thereof.

The frame C is of U form with its ends pivotally connected at the points indicated 90 at 21 to the sides of the frame F for the purpose of permitting the adjustment of the frame C to properly embrace the chin of the wearer. The frames F and C and the mask M are provided with conventional 95 snap fasteners indicated at 22, arranged as shown, and which coact to secure the mask to the frames so that the latter will function to maintain the mask as a whole in contiguous relation to the face.

100 It is important to note that the mask is so constructed as to completely cover the mouth and to extend to all portions of the face which are shaven so that when used as a face steam pack it will operate to thoroughly soften the beard and thus facilitate shaving.

105 Although I have herein shown and described only one form of face pack embodying my invention, it is to be understood that various changes and modifications may be made herein without departing from the

spirit of the invention and the spirit and scope of the appended claims.

I claim:

1. A face pack comprising a mask including a portion adapted to receive the chin and other portions adapted to overlie the cheeks and having extensions adapted to overlie the sides of the face at points forward of the ears, and a device for supporting the mask on the head comprising a pair of frames, one of the frames being of ovate form and adapted to engage around the head of the wearer to overlie the underside of the chin receiving portion of the mask, the cheek overlying portions of the mask and the extensions thereof, the other of the frames being of **U** form and pivotally connected at its ends to the ovate frame in such position that it is adapted to overlie the chin receiving portion of the mask, means for securing the ovate frame to said extensions of the mask, and means for securing the second mentioned frame to the chin receiving portion of the mask, whereby the mask will be supported on the head in contiguous relation to the face.
2. A face pack comprising a mask includ-

ing a portion adapted to receive the chin and other portions adapted to overlie the cheeks and having extensions adapted to overlie the sides of the face at points forward of the ears, and a device for supporting the mask on the head comprising a pair of frames, one of the frames being of ovate form and adapted to engage around the head of the wearer to overlie the underside of the chin receiving portion of the mask, the cheek overlying portions of the mask and the extensions thereof, the other of the frames being of **U** form and pivotally connected at its ends to the ovate frame in such position that it is adapted to overlie the chin receiving portion of the mask, co-acting fastening members on said extensions of the mask and on the ovate frame for detachably securing the latter to the extensions, and co-acting fastening members on the chin receiving portion of the mask and on the second mentioned frame for securing the latter to the chin receiving portion, whereby the mask will be supported on the head in contiguous relation to the face.

WILBERT L. DREW.
